UNITED STATES PATENT OFFICE.

ALTON H. BOWMAN, OF ALLENTOWN, PENNSYLVANIA.

VENDING-MACHINE.

1,138,075.

Specification of Letters Patent.

Patented May 4, 1915.

Application filed August 20, 1912. Serial No. 715,998.

To all whom it may concern:

Be it known that I, ALTON H. BOWMAN, a citizen of the United States, residing in Allentown, county of Lehigh, State of Pennsylvania, have invented certain Improvements in Vending-Machines, of which the following is a specification.

My invention relates to certain improvements in vending machines of the type in 10 which the coin releases the tray and allows the article vended to be projected from the machine.

One object of my invention is to construct a vending machine of this type so that the 15 coin will push the retaining means out of the path of the tray, enabling the tray to be forced in to its full extent to receive the article vended; the tray being forced out again by the action of a spring, or its equivalent; the retaining means being re-set after 20 the tray has been projected.

A further object of the invention is to construct the casing of the vending machine so that it can be made very narrow in order 25 to locate it on the posts or panels of a passenger car between the windows, as the invention is particularly adapted for use on trolley cars scheduled for long trips and a 30 passenger, by placing a coin of the proper denomination in the slot, will receive in exchange chocolate, chewing gum, or other commodities.

In the accompanying drawings:—Figure 1, is a perspective view showing my improved vending machine located between the 35 windows of a trolley car; Fig. 2, is a sectional plan view on the line 2—2, Fig. 7; Fig. 3, is a transverse sectional view on the line 3—3, Fig. 2; Fig. 4, is a longitudinal 40 sectional view on the line 4—4, Fig. 2; Fig. 5, is a detached perspective view of the partition with the tray; Fig. 6, is a perspective view of the trigger which retains the tray in the projected position; and Fig. 7, is a 45 vertical sectional view drawn to a reduced scale showing the parts in position.

Referring to the drawings, A is the casing made in a single casting and narrow so as to fit a panel between the windows of a 50 passenger or trolley car, as illustrated in Fig. 1. At the upper end of the casing is a forked projection a, which engages a headed screw b on the framework B of the car. At the other end of the casing is a projection a' having a slot through which extends a staple b' on the post B and a lock b² may

be placed in position to firmly lock the casing to the car body. Other means of fastening, however, may be employed, without departing from the essential features of the 60 invention.

c is the slot in the casing through which a coin is inserted.

c' is the coin-way through which the coin passes to the slot d in the partition D. 65

A' is the slideway for the chocolate, chewing gum, etc. This slideway is directly above the platform e of a tray E. The tray is stepped so as to form a delivery section e'. 70

The commodity to be vended normally rests on the platform e, but when the tray is forced in after the coin is inserted in the slot, the commodity falls onto the portion e' and the shoulder e² pushes it out of the casing when the tray is forced out by its spring. 75 In the inner surface of each side wall of the casing is a groove a² into which extend ribs d' on the edge of the partition D. This partition is of the same depth as the casing, so that when the casing is secured in position 80 the partition is held against movement. Depending from the partition D are lugs d² and secured to these lugs are plates f, f' which regulate the width of the passage and, consequently, prevent the passage of coins 85 or slugs of a greater width than that determined upon when making the vending machine. One of these plates f is flanged; the other plate f' being V-shaped.

While this construction holds the coin 90 properly in position; when the coin is released there is nothing to interfere with its dropping into the receptacle below the partition.

I is a trigger made of wire, in the present 95 instance, as shown in Fig. 6.

i, i' are the pivot sections of the trigger adapted to bearings in the flanges f² of the plate f and between the two pivots is a V-shaped extension i² which extends on each 100 side of the V-shaped plate f' and at the base of this V-shaped projection is a lateral extension i³ forming a seat for the coin when it passes into the slot d. This extension projects across the space between the two plates 105 f, f' and retains the coin in the slot until it is moved out of the path of the coin, when the tray is forced in.

n is a long arm of the lever, having at its outer end a vertical portion n' which extends 110 through a slot d³ in the partition D, and at the upper end of this vertical section is a

transverse section n^2 having a short vertical projection n^3 which extends into the path of the tray E, as illustrated in Figs. 4 and 5, so that while the trigger is in the position illustrated, it is impossible to force the tray into the casing, but as soon as the outer end of the arm n is raised by the coin moving the portion i^2 laterally, then the tray is in position to be forced into the casing and as the tray is pushed in the horizontal portion n^2 of the trigger I travels up on the inclined or cam surface g of the tray E, as illustrated in Fig. 5, raising the arm n of the trigger and at the same time withdrawing the projection i^3 , which supports the coin, and allows the coin to fall into the receptacle under the partition. The long arm n of the trigger is held in its raised position until the tray completes its full inward movement and when the tray is projected it again assumes its normal position ready to receive and support another coin.

On the underside of the tray E is a lug e^3 , which extends through a slot d^4 in the partition D. Attached to this lug is a plate m having a depending portion to which is attached one end of a coiled return spring M. The other end is attached to a post m' depending from the partition D.

In order to prevent the return of the tray before it has completed its full movement into the casing, I provide a spring detent pawl s, which is pivoted to a projection on the plate m . This pawl engages teeth s' on the underside of the partition D. There is a space at each end of the row of teeth, as illustrated in Fig. 4, to allow the pawl to swing on its pivot, so that when the tray is pushed in the pawl will hold the tray from moving outward under pressure of its spring M; the pawl ratcheting on the teeth until the tray has been moved into the casing to its full extent, when the end of the pawl will enter the deep recess and will swing on its pivot, due to the pressure of its own spring, to a position which will allow the main spring M to force the tray out of the casing without interference of the pawl. This construction insures the full movement of the tray.

In the front of the casing directly above the slot p for the tray is a vertical slot p' suitably glazed so that the articles vended are visible.

I preferably locate a magnet V in the path of the coin, as illustrated in Fig. 7, to prevent the passage of any iron slugs into the casing, as the magnet will attract and will hold these slugs.

It will be seen by the above construction that I am enabled to make an inexpensive, yet practical and simple, vending machine, elongated in shape and so narrow as to be placed between the windows of a car; the machine correctly and quickly feeding small

articles, such as chocolate, chewing gum, etc., to the tray upon the insertion in the slot of the proper coin.

The coin is inserted in the slot c in the casing and passes the magnet, afterward traveling in a circuitous path, as shown in Fig. 7, and drops into the slot d in the partition D. The coin, as it enters the slot d , bears upon the portion i^2 of the trigger I, turning the trigger on its pivot so as to lift the end n^3 of the trigger clear of the tray; the coin finding its seat on the portion i^3 of the trigger. The parts are then in position for the tray to be forced in and a series of wrapped chocolates, for instance, are placed one upon another in the guide A'; the lower one resting directly upon the platform e of the tray. As the tray is pushed in the beveled or cam surface g of the tray passes under the portion n^2 of the trigger and turns the trigger on its pivot, withdrawing the portion i^3 from under the coin; allowing the coin to drop into the receptacle under the partition and, after the tray is pushed into the casing to its full extent, it is released from the control of the pawl; its spring forcing it out. In the meantime the edge of the platform is passed, allowing the cake of chocolate to drop upon the portion e' in front of the wall e^2 ; said cake of chocolate being forced out of the casing with the tray. The platform e closes the opening p in the casing.

While I have illustrated my invention as applied to a single narrow casing, it will be understood that it may be applied to one of greater width where other commodities are to be vended or where a series of vending elements are contained in one casing.

I claim:—

1. The combination in a vending machine, of a casing; a transverse partition therein separating the compartment holding the commodity from that for the reception of the coins; a sliding tray mounted on the partition and less in width than the casing and having a platform supporting the commodity, the partition having a coin slot located between one edge of the tray and the casing; a trigger pivotally mounted close to the coin slot and having one arm with a lateral projection at the lower end and another arm extending across the casing and through the partition, said arm having a horizontal portion; a cam on the tray arranged to pass under the horizontal portion of the last mentioned arm of the trigger after a coin is located in the slot, so as to release the coin when the tray is pushed into the casing.

2. The combination in a vending machine, of a casing having an internal longitudinal groove at each side; a slotted transverse partition having ribs fitting the grooves; a tray movably mounted in the partition and hav-

ing a depending lug adapted to the slot in the partition; a spring secured to the lug and to the partition to return the tray to its normal position after it is forced into the 5 casing; a wire bent in the form of a trigger pivotally mounted on the underside of the partition; said partition having a coin slot therein; one arm of the wire trigger being bent to extend into the coin slot; the other 10 arm of the trigger being bent to engage the sliding tray so that when the coin passes into the coin slot it will turn the trigger on its pivot, releasing the tray and allowing it to be pushed in to receive the commodity. 15 3. The combination of a casing; a transverse horizontally arranged partition having extensions; a tray arranged to slide on the partition; means for preventing the tray returning after being once moved out until 20 it is moved to the full extent, said tray being less in width than the casing, said partition having a coin slot between the side of the tray and the casing and said partition hav-

ing an opening at the opposite side at a point back of the tray when it is projected; 25 plates secured to the extensions of the partition, forming a continuation of the coin slot; a trigger pivotally mounted under the partition and having a V-shaped arm provided with a projection at its lower end arranged 30 to retain the coin in the slot, the trigger having another arm projecting through the opening in the partition having a right angled extension projecting over a portion of the tray when the tray is pushed in, said 35 portion of the tray having an arm for engaging the last mentioned arm of the trigger so as to lift it and release the coin from the control of the other arm.

In testimony whereof, I have signed my 40 name to this specification, in the presence of two subscribing witnesses.

ALTON H. BOWMAN.
